UNITED STATES PATENT OFFICE.

JOHN J. HEYS, OF LYNN, MASSACHUSETTS, ASSIGNOR, BY MESNE ASSIGNMENTS, TO THOMAS G. PLANT, OF BOSTON, MASSACHUSETTS.

SEWING-MACHINE.

No. 905,311.

Specification of Letters Patent.

Patented Dec. 1, 1908.

Application filed June 21, 1905. Serial No. 266,244.

To all whom it may concern:

Be it known that I, JOHN J. HEYS, a citizen of the United States, residing at Lynn, in the county of Essex and State of Massachusetts, have invented an Improvement in Sewing-Machines, of which the following description, in connection with the accompanying drawings, is a specification, like letters on the drawings representing like parts.

10 My invention relates to sewing machines, and particularly to lock stitch machines employing a curved needle and awl. These machines are employed principally in the stitching of outsoles to the welts of boots and shoes. Machines of this general type are illustrated in U. S. Letters Patent to Dancei No. 366,935, dated July 19, 1887, and French and Meyer, No. 412,703, dated October 8, 1889.

20 My invention aims to simplify the mechanism of machines of this class, not only for the purpose of economizing in cost of construction, but also to increase the certainty of operation and durability thereof, and to render the parts more conveniently accessible for purposes of adjustment and repair.

The various features of my invention will be best understood from a description of the best embodiment thereof now known to me, and which I have illustrated in the accompanying drawings, it being understood, however, that my invention is not limited to the particular embodiment thus selected for illustrative purposes. This illustration and description are intended for those skilled in the art, it being assumed that the general construction and operation of such machines are familiar to the reader.

40 In the drawings,—Figure 1 in front elevation, partially broken away, shows a machine illustrating my invention; Fig. 1^a, a sectional detail to be referred to; Fig. 2 is a top or plan view of the machine, Fig. 1; Fig. 3 is a left-hand, side elevation of the machine Figs. 1 and 2; Fig. 4 is a right-hand side elevation of said machine; Fig. 5 is a vertical cross section on the dotted line 5—5, Fig. 1, looking to the left or towards the middle of the machine; Fig. 6, a similar cross section on the dotted line 6—6, Fig. 1, also looking to the left; this view showing principally the needle actuating mechanism, thread arm actuating mechanism, and

parts of the looper mechanism; Fig. 7, a detail showing a part of the awl actuating mechanism; Fig. 8 is a vertical cross section on the dotted line 8—8, Fig. 1, looking to the right, toward the middle of the machine, Fig. 1; Fig. 9 is a horizontal sectional detail on the dotted line 9—9, Fig. 8, showing the looper mechanism; Fig. 10 is a detail illustrating a part of the thread measuring mechanism for measuring the thread for different thicknesses of stock.

In the particular embodiment of my invention selected for illustration herein and shown in the drawings, referring first to Figs. 3 and 4, the machine head is carried upon a standard A, which is preferably tubular at its upper end and provided with suitable clamping means to receive the vertically adjustable stem A'. This stem has its upper end provided with a flanged head A², to and upon which is bolted the head casting B, extended laterally in both directions and carrying at its opposite ends (see Figs. 1 and 2) the supporting columns b, b; the same being removably secured to said head casting for convenience in assembling the machine and for removing its parts for repair, etc. In the upper ends of these supporting columns b is journaled a main or camshaft C, upon which are mounted the various cams from which the different motions are obtained, and which will be referred to from time to time in this description. This camshaft is extended to the left, Figs. 1 and 2; beyond its end supporting column b, to receive the usual belt pulley or wheel b', which may be belted to and driven from any suitable driving or countershaft.

Viewed from the front of the machine, the head casting is provided centrally (see Fig. 1) just below the shuttle with the forwardly and upwardly extended rib or arm B² (see Figs. 5 and 4), to the front end of which (see Fig. 1) is secured the work support b², of usual shape and slotted transversely for the passage therethrough of the usual curved awl and needle.

Referring to Figs. 5 and 7, the awl is shown at d, it being mounted in a carrier d', fulcrumed loosely upon the horizontal pivot or pin d², mounted in the upper end of a bracket e of the feed slide e'. The awl carrier (Fig. 7) is provided with a segmental gear d³, driven by the segmental gear d⁴,

upon the front end of the awl lever d^6 , that extends through to the back of the machine (see Fig. 5) and is there fulcrumed loosely upon the horizontal shaft d^6 , mounted in an upwardly extended arm B^3 upon the head casting B referred to. Between its ends this awl lever d^6 (see Fig. 5) is provided with a roller stud d^7 , that travels in a box cam upon the inner face of the cam disk D (Figs. 1, 2, 10 and 5), fast upon and rotatable with the camshaft C referred to. Rotation of this camshaft causes the awl lever to be vibrated vertically, and, through its said segmental gear and awl carrier gear d' (Fig. 7) to 15 oscillate the awl d , to cause it to rise through the work support b^2 , to penetrate the stock and afterwards to drop away from the work in advance of the descending needle.

The awl is employed to feed the work; 20 consequently, when it is in use, it must be moved laterally from right to left (Fig. 1), and for this purpose it is mounted, as stated, in the bracket e of the feed slide e' . This feed slide (see Figs. 1, 2, and 5) is mounted to slide transversely at the front of the machine in the slideway e^2 , which projects from and is a part of the head casting B , referred to. To reciprocate this slide said upright awl carrying bracket e (see Figs. 1 and 1^a) is 25 provided with a threaded sleeve e^8 , screwed transversely into and practically through said bracket, and therefore adjustable therein like a screw by rotating it in one or the other direction. To facilitate this rotation the flanged head e^4 is knurled, and also, for convenience, is provided with radial holes for the reception of an operating pin which may be inserted in one or the other thereof for rotating the sleeve step by step in either 30 direction. This sleeve is internally threaded to receive the threaded eye-bolt e^5 through the eye in which is extended the pivot bolt e^6 upon the inner end of the horizontal feed lever e^7 . This lever is extended to the right (Figs. 1 and 2) and at its outer end is shaped to 35 constitute a handle by which it may be swung towards and away from the operator standing at the front of the machine.

Between its ends the feed lever e^7 has 40 pivoted on its upper side a slide block e^8 , adapted to slide in the arc grooved actuator arm e^9 , having a yoke-like hub e^{10} , shown best in Fig. 1, fulcrumed vertically on a bearing e^{11} , secured to and upon the head 45 base B . This yoke-like hub e^{10} at its upper side, is provided with an inwardly extended, horizontal arm e^{12} , carrying at its end the upwardly extending roller stud e^{13} , that travels in the peripheral path cam e^{14} of the 50 cam disk E , also fast upon the camshaft C . Rotation of this cam operates to vibrate horizontally the arc grooved arm e^9 , which transmits its vibrations through the lever e^7 to the feed slide and the awl thereon; and 55 this lateral vibration or feeding movement

takes place without disturbing the toothed engagement between the awl segment d^3 and its actuating lever segment d^4 which oscillate or vibrate the awl in its curved vertical path.

The operator may vary the extent of feed 60 at each movement of the feed slide, and while the machine is in operation by swinging the actuating lever e^7 towards and away from him, thereby to position the slide block e^8 further from or nearer to the fulcrum of 65 vibration of the cam actuated arm e^{12} . Said lever e^7 is arranged to travel over a curved bearing plate e^{15} (Figs. 2 and 1), which is provided with a closely arranged series of holes for the reception of stop pins e^{16} . By 70 adjusting these stop pins in the different holes referred to the limit of movement of the lever in either direction is obtained; or it may be locked against movement in either 75 direction and in any position of the lever.

The needle and its operating mechanism are best shown in Figs. 2, 3, 6, and 8. Referring first to Fig. 6: the curved needle is 80 shown at h , the same being adjustably mounted like the awl, in a carrier h' , loosely fulcrumed upon a horizontal carrier pin h^2 , fast in the front end of the rib or support B^2 85 that carries the work support.

The needle segment h' is provided with a segmental gear h^3 , driven by the segmental gear h^4 , upon the front end of the long needle actuator lever h^5 , extending through to the back of the machine and, like the awl actuator lever, fulcrumed upon the same shaft d^6 . Between its ends said actuator lever h^5 is 90 provided with a roller stud h^6 , that travels in a path cam h^7 in the right-hand face of the cam disk H , likewise fast upon the cam-shaft C .

Rotation of the camshaft and its cam H , 95 causes the needle actuator lever h^5 to rise and fall and, through its segmental gear and that upon the needle carrier, vibrate the latter and its needle, to cause the latter to oscillate vertically to enter and leave the 100 stock from above, following the awl movements described. The awl rises through the stock in a position at the right of the needle, and while in the stock is moved by the feed slide to the left (Fig. 1) until its vertical 105 alignment coincides with that of the needle, when it is withdrawn from the stock, the needle following it down from above and entering the stock through the puncture made and left by the awl. The mechanisms 110 are preferably so timed that the point of the needle enters the stock from above, before the awl is completely withdrawn from below; thus to leave the stock always under 115 positive and complete control.

To support the needle and guide it in its curved path I have provided a usual needle guide h^8 , loosely mounted upon the shank of the needle carrier and provided with a segmental gear h^9 , that is engaged by a pinion 120

h¹⁰ upon a short shaft *h¹¹*, loosely mounted in said middle frame support *B²*. This short needle guide shaft *h¹¹* (Figs. 1 and 3), extends completely through said support *B²*, 5 and is provided at the opposite or left-hand side thereof with a pinion *h¹²*, clamped in adjusted position on said shaft by a screw *h⁸*, and driven by a segmental gear *h¹³* upon the end of an arm *h¹⁴*. This arm is rearwardly extended and is made fast upon one 10 end of the horizontal cross-shaft *h¹⁵*, (Fig. 3,) loosely mounted in bearings in the said frame support *B²*. This cross-shaft *h¹⁵* extends to the right (Fig. 1) and is provided 15 at its end and between the large cams *D* and *E* with an upwardly extended arm *h¹⁶* (Figs. 1 and 5), provided at its upper end with a roller stud *h¹⁷*, that travels in a path cam *h¹⁸*, in the right-hand face of said cam disk *D*. 20 Rotation of said cam disk causes said arm *h¹⁶* to be vibrated to operate through its shaft and the segmental gear *h¹³* and its pinion *h¹²* and connections described, to move the needle guide forward and downward 25 with the needle until it rests substantially upon or near to the work permitting the needle to complete its movement through and relative to said guide, and after the needle has commenced its upward, retractile 30 movement, the guide goes back with it.

The rotative position of the pinion *h¹²* upon its carrying shaft may be varied at will, thereby to determine the position of the needle guide. The guide itself is detachably 35 mounted in usual manner upon its carrier, to enable it to be readily changed to accommodate needles of different numbers.

The looper for carrying the thread around the barb of the needle, after the latter has 40 penetrated the stock from above, is shown at *i*, Fig. 1, and also in Figs. 3 and 9. This looper, itself of usual construction, is held clamped by its shank in the split end 45 of a looper carrier *i'*, mounted upon a vertical pivot *i²* (Figs. 9 and 1), said pivot being carried by an ear *i³*, extended laterally from a looper slide *i⁴*, shown best in Fig. 9. This slide is mounted to reciprocate from front to back of the machine upon horizontal 50 guide rods *i⁵* (Fig. 8), supported at their inner ends in a bracket *i⁶*, fast upon the head base *B*, said guide rods at their front ends being supported in a yoke *i¹⁰*, bolted at its bottom, to the base of the bracket *i⁶*. At its 55 upper end (Fig. 8) said looper slide *i⁴* is provided with a stud *i¹¹*, which (Fig. 2) enters and travels in a path cam *i¹²* (dotted lines, Fig. 3), formed in the right-hand face of the large cam disk *I* (Figs. 1 and 2) fast 60 upon the camshaft *C*. Rotation of this cam operates through the parts described to give to the looper its forward and back motion. To give to the looper itself lateral movements which when combined with the forward and back movements, produce the re-

sultant circular travel necessary to carry the thread around and lay it in the barb of the needle. I have extended the looper carrier *i'* (Fig. 9) beyond or to the left of its pivot *i²* and have forked its end to receive the slide 70 block *i¹³* upon the end of a horizontal arm *i¹⁴*, fulcrumed at its rear end upon a vertical stud *i¹⁵*. The pivot by which said block *i¹³* is mounted upon said arm *i¹⁴*, is prolonged vertically to receive the roller *i¹⁶*, that enters 75 and travels in the peripheral path cam *i¹⁷* (Fig. 2) upon the cam disk *H*.

The resultant movement imparted to the looper by the mechanisms described, is such that said looper standing normally in its innermost retracted position, is advanced forward and to the right (Fig. 1) as the needle descends, to lay its thread at the front of the needle, and, as the needle retracts or rises through the work, said looper returns partially, until it reaches a position substantially in the line of draft of thread from the needle to the thread truck, where it remains at rest until substantially all thread has been drawn upward through it and the stitch has been set before it returns to its innermost position from which it first started. By thus positioning the looper in line with the natural draft of the thread, I avoid all danger of abrading and injuring the latter during 90 the formation and tightening of the stitch. The position of the looper in its carrier may of course be adjusted forward and backward, also vertically, by means of the split clamp at the front of the looper carrier, and 100 the range of movement of the looper may be adjusted laterally by sliding the cam disk *H* longitudinally of the camshaft *C*.

The thread finger which in machines of this class is employed to engage and hold 105 the thread at the left of the needle while the looper has laid it around and is holding it at the opposite side, which withdraws into the machine to measure off enough thread at the left of the needle to prevent the thread reaving across the needle barb during the subsequent formation of the stitch, is shown at *j* (Figs. 1 and 6). This thread finger is formed upon the lower front end of an upwardly and rearwardly inclined finger bar 110 *j'* (Fig. 6) mounted to slide in the support *B²*. At its upper and inner end said finger bar is provided with a rack that is engaged by a segmental gear *j²*, depending from a pivot *j³*, carried by an arm of the shuttle case 115 to be described. This segmental gear (Fig. 6) at its lower inner end, carries a roller stud *j⁴*, that travels in a path cam *j⁵*, in the right-hand face of the large disk cam *H*, referred to. By removing the pivot screw *j³* and 120 lifting slightly this segmental gear *j²*, to disengage its teeth from the finger rack described, the thread finger and its bar may be drawn straight out from and at the front of the machine, whenever occasion arises for 125 130

removing it. When this segmental gear is so lifted, its roller stud slides along in its path cam, retaining its engagement therewith. This construction is much simpler than any now known to me for actuating and for permitting the removal of the thread finger.

I will now describe the thread measuring and take-up mechanism.

Referring to Fig. 3 at the rear of the machine and upon the head stem A', is mounted the thread wheel m_1 , over which the thread is drawn from any suitable or usual wax pot, not herein shown. The thread from this wheel is led straight through the stem A', 10 a guide tube m_2 , being provided therein for the purpose. Issuing from the front end of said tube, the thread is carried to and about the tension wheel m_3 of any suitable or desired construction. Herein (see Fig. 1) the 15 tension is under the control of a spring m_4 and one or more adjusting nuts m_5 . From this tension wheel the thread (Fig. 3) is carried upward and over the measuring truck m_6 , and down again to and about the stationary thread truck m_7 . This measuring truck m_6 is made vertically reciprocable to enable it to measure off the thread, said truck for the purpose being mounted on the outer end of an arm m_8 , fast upon the end of 20 a short oscillatory shaft m_9 mounted in the head support B', referred to (see also Fig. 8). This short shaft m_9 (see Figs. 5 and 10) is extended to the right completely through said head support B', and at the right thereof, is provided with a downwardly and forwardly extended arm m_{10} , fitted at its free end with an adjustable stop screw m_{11} . The short shaft m_9 is surrounded by a loose sleeve m_{12} , which is provided outside of said 25 support and just inside of said stop screw carrying arm m_{10} , with an arm m_{13} . At its upper end this arm m_{13} carries rigidly a measuring head m_{14} , grooved at m_{15} . At its lower end this grooved measuring head has 30 a depending ear m_{16} (Fig. 5) that stands opposite the stop screw m_{11} , referred to and furnishes means for moving the latter with a certain amount of previous lost motion represented by the separation of the one 35 from the other. In the groove m_{15} of this measuring head is the T-headed slide block m_{17} , to which is jointed at m_{18} the forward end of an actuator rod m_{19} , that extends to the back of the machine and is there 40 justably connected to the lower slotted end of an arm m_{20} . The hub m_{21} of this depending arm m_{20} , is provided (Fig. 4) with a horizontally extended arm m_{22} , carrying at its free end a roller stud m_{23} , that travels in 45 a path cam m_{24} in the inner or left-hand face of the large cam disk E. Rotation of this cam operates through the bell crank lever formed by these arms m_{25} , m_{26} (Figs. 4 and 5) and the actuator rod m_{19} to reciprocate 50 the slide block m_{17} from front to rear of the

machine, and imparting to the grooved measuring head m_{14} a corresponding but rocking movement. The length of reciprocation of the slide block m_{17} being constant, it follows that the extent of rocking or oscillating movement imparted thereby to the grooved measuring head, will vary according to the distance of said slide block from the center of oscillation, and the oscillation of the measuring head transmits an intermitting and quick oscillatory or vibrating movement to the stop screw carrying arm m_{11} and the measuring arm and truck m_6 to measure off the thread, the time of said movement and the extent thereof depending upon the adjustment of said stop screw and the lost motion thereby permitted before it is engaged by the measuring head. To control its position, said slide block m_{17} is suspended at m_{27} , in the lower end of a link m_{28} , carrying loosely at its upper end a stud m_{29} , adapted to be clamped in adjusted position in a slot m_{30} , in the inner end of a presser-foot lever m_{31} . This lever is fulcrumed upon a stud m_{32} , in the head support B', and at 70 its front end is provided with a downwardly turned and properly shaped presser-foot m_{33} , rising from which is the handle m_{34} , by which said presser foot may be thrown upward and backward to free the work or to 75 permit of the placing of the work upon the work support b^2 that stands beneath and opposed to the presser-foot. The presser-foot lever m_{31} at its inner end (Fig. 5) is segmentally geared for engagement by the 80 pinion m_{35} , (Figs. 5, 1 and 4), formed on the left-hand or inner end of a horizontal, laterally extended shaft m_{36} , mounted in suitable bearings on the head. Attached to this 85 pinion shaft (Figs. 1 and 4) is one end of a flexible connection or chain m_{37} , that leads to the back of the machine, where it is connected to a tension spring m_{38} controlled by an adjusting device m_{39} , carried upon the 90 head. This spring, by its pull upon said chain, tends to rotate said pinion m_{35} (Fig. 5) in the direction of the arrow and through the segmentally geared presser-foot lever, to throw the presser-foot downwardly upon and to clamp the work whatever be the 95 thickness of the work. The position assumed by the presser-foot when thus pressed upon the work varies, of course, according to the thickness of the work between it and the fixed work support b^2 , and this variable 100 position of the presser-foot and its lever m_{31} (Fig. 5) necessarily and correspondingly varies the position of the slide block m_{17} suspended from it.

As the presser foot is lifted to accommodate thicker work, its connected slide block is depressed and in moving nearer to the axis of oscillation of the measuring head m_{14} will tip the measuring head toward the back of the machine and swing its depending 110

ear m^{13} nearer to the opposed stop screw m^8 thereby to reduce the lost motion between said ear and stop screw before the latter is engaged and moved by the ear throughout the remaining movement of the measuring head. Because it is now nearer to the axis of rotation of the measuring head, the oscillation of said head by and from the bell crank lever m^{17} , m^{19} will be enlarged. The result of this reduced lost motion between the head and stop screw and enlarged oscillation of the head is to cause said oscillation to commence earlier in the cycle of operations of the machine and to enlarge the movement of the thread measuring truck m^4 to cause it to measure off additional thread proportional to the additional thickness of the work, so as to locate the thread lock in the same position proportionately, between the top and bottom of the thick work that it was adjusted to assume in the thinner stock. A reduction in thickness of work will cause the presser foot to drop nearer to the work support, thereby raising its lever and the slide block and reducing the oscillation of the measuring head and resultant movement of the measuring arm and thread movement.

With the foregoing construction an automatic variation of the amount of thread is provided by the slide block m^{14} and its connections, while further adjustment may be had, if desired, through the adjusting screw m^8 , bolt m^{23} and slot m^{24} , or the adjustable connection between the rod m^{16} and arm m^{17} .

During the feed of the work the presser-foot should be pressed upon the top thereof only under the tension of the spring described; but, at the close of the feed and during the period of formation and setting of the stitch, said presser-foot should be locked fixedly in position to prevent any possible displacement of the work; and this locking mechanism, whatever its construction, must be capable of catching and locking the presser-foot in any position in which it may find it, whether upon thick or thin stock. In the construction shown a band brake n is employed for this purpose. This brake band surrounds the enlarged end of the pinion shaft m^{20} , one of the ends of said band being provided, Fig. 4, with an ear n' , resting in contact with the stop screw n^2 , mounted in an arm n^3 , secured to a part of the adjacent column b of the head. The other and opposed end of said brake band (Fig. 4) is connected by a pin n^4 , with a short actuator lever n^5 , suspended by a connecting rod n^6 from a crank pin n^7 on the end of the main cam shaft C of the machine. This crankpin is bushed in the end of the connecting rod described, to provide for wear and renewals without disturbing the cam-shaft itself. Referring to Fig. 4, the brake actuator lever n^5 is extended beyond its sus-

pension point and is provided at its back end with an irregularly or cam faced head n^8 , that plays up and down in front of a fixed roller stud n^9 on the head column b . At the proper time in every rotation of the cam-shaft, this brake actuator n^5 is depressed by the crank n^7 , and the cam faced head n^8 on the back end of said actuator acting against the roller stud n^9 throws the front end of said actuator towards the front of the machine to tighten the brake band and lock the presser foot.

Returning now to Figs. 3 and 8: The thread from the measuring truck is carried, as stated, downward to and about the stationary thread truck m^{34} , thence upward and over the auxiliary take-up mounted in a short lever m^{36} , fulcrumed at m^{37} , and normally lifted by the light spring m^{38} . The extent of movement of this auxiliary take-up is limited by the two stops 3 and 4. From this auxiliary take-up m^{39} , the thread is carried downward to and about the take-up o , thence again upward to and through the looper i , previously described. The take-up comprises a pulley or truck upon a vibrating arm o' , fast upon a horizontal oscillatory shaft o^2 , shown at the lower left-hand portion of Fig. 1, and mounted in suitable bearings o^3 in the machine on the head castings. Near its left-hand bearing said shaft o^2 is provided with an upright arm o^4 , the upper end of which is connected by a link o^5 , with the lower end of the cam lever o^6 , fulcrumed at o^7 in a bearing on the column b . This lever at its upper end carries a roller stud o^8 , that travels in a path cam o^9 in the left-hand face of the cam disk I (Figs. 1 and 3). At every rotation of the cam-shaft, this cam I operates gradually to raise the take-up o , to contribute thread to and for the formation of the stitch and then upon the completion of the stitch formation, to depress said take-up sharply, to tighten or set the stitch.

Referring to Fig. 3: It will be noticed that the measuring truck m^4 is at the left of the fixed thread truck m^{34} and acts upon the thread before the latter reaches the said fixed thread truck, while the take-up o acts upon the thread at the right of said fixed truck and between the latter and the work. In order that the measuring arm in measuring off its thread may pull always from the wax-pot or thread supply, and not from or move the auxiliary take-up m^{39} , said thread should be locked beyond or at the right of said measuring arm so that the draft of new thread shall come wholly from the thread supply. In order also for the take-up properly to set or tighten the stitch, it is necessary that the thread be locked back of the take-up or to the left thereof (Fig. 3); otherwise it would draw thread from the thread supply, instead of from and to set the stitch. I accomplish both these results by 130

providing a thread lock in coöperation with the stationary or fixed thread truck m^34 , that is located between the measuring device and the take-up. This thread lock (see Fig. 3) 5 consists of a locking arm p , fast on a lock shaft p' , that extends horizontally beneath the feed slide guide e^2 (Fig. 1) and carried in bearings depending therefrom. Between its ends said lock shaft p' has a depending 10 arm p^2 , connected at its lower end by a link p^3 (Fig. 4) with the lower end of a depending cam lever p^4 , fulcrumed at p^5 and having its upper end (Fig. 5) provided with a roller stud p^7 that travels in a cam p^6 in the 15 right-hand face of the large cam disk D. At each rotation of said cam disk the thread locking arm p (Fig. 3) is, by the mechanism described, swung to the right (Fig. 3) to press the thread against the periphery of the 20 fixed thread truck, thereby to lock the thread at that point against movement in either direction; this action, of course, locking the thread truck itself against rotation.

In the operation of the machine with the 25 thread locked between the locking device p and fixed truck m^34 as the awl rises to penetrate the work the measuring device m^5 is lifted to draw a supply of thread from the thread supply and to measure the same according to the thickness of the work. The 30 take-up is then at rest in its lowest position.

Immediately after the measurement of the thread and, just about as the needle reaches its lowest position and the looper moves to 35 lay the thread in the path thereof, the thread lock is released and the take-up commences to give off its thread to the ascending needle. The lock remains released until the take-up has reached its highest position and has proceeded somewhat in its return or downward 40 movement, when it is restored, in order that in its further downward movement said take-up may tighten and set the stitch without drawing from the thread supply.

45 The auxiliary take-up m^39 described performs the function of the usual auxiliary take-up; namely, the prevention of any slack in the thread during the stitch formation.

50 Taking up now the shuttle mechanism: Reference may be had to Figs. 1 to 3, inclusive. The shuttle S is mounted vertically at the front of the machine in the position common to machines of this type, and is 55 made to oscillate about a horizontal axis extending from front to rear of the machine. This shuttle is mounted to oscillate in a segmental case which is formed of a back portion s' rigidly secured to the head 60 support B² referred to and a front or cap portion s^2 removably secured thereto by screws s^3 (Fig. 1).

The shuttle itself is of the usual type in outline and, presenting a point s^5 (Fig. 1) 65 shaped to enter the loop drawn up by the

needle, remove said loop from the needle and carry it around the bobbin t which is carried by the shuttle.

The shuttle is oscillated from behind by a short shaft, extending towards the front of the machine and carrying at its front end means to engage respectively the point and tail portions of the shuttle. This shaft is rocked to oscillate the shuttle carrier and shuttle by means of a pinion s^{10} (Fig. 2), 70 formed or secured upon the inner end of said shaft and engaged by the segmental and slightly beveled gear s^{11} upon the front end of a cam lever s^{12} that extends through to the back of the machine and is mounted, like 75 the other cam levers, upon the shaft d^6 referred to. Between its ends said cam lever s^{12} (see dotted lines Fig. 8) is provided with a roller stud s^{13} that travels in a path cam s^{14} formed in the left-hand face of the large 80 cam disk H. At every rotation of the cam-shaft the shuttle is given one complete oscillation to cause its point to remove a loop from the needle and cast it about itself and its thread; after which it is returned to its 85 original position for engagement with a new loop.

In the present instance I have provided means for positively locking the bobbin to the shuttle during the oscillatory movement 90 of the shuttle, releasing the bobbin, after the shuttle has come to rest for a sufficient period only to permit the necessary thread to be reeled therefrom,—which is during the effective action of the take-up,—after which 95 the bobbin is again locked to the shuttle before the latter commences its return movement. This lock may be friction or positive. As here shown I employ a positive lock and to this end I provide the periphery of the 100 outer flange of the bobbin with a series of teeth t' , adapted to be engaged by correspondingly toothed locking block t^2 , mounted and radially movable in the shuttle. The shuttle face projects to the front somewhat 105 beyond the faces of the bobbin teeth, so that there is no danger of the thread loop catching upon such teeth. The shuttle case (see 110 Figs. 1 and 2) is provided at the left with a laterally extended ear t^3 upon which is vertically pivoted at t^4 a horizontal rocking carrier t^5 . This carrier at its front side is provided with an arm t^6 , that reaches around in front of the shuttle and is provided at its free end with a releasing finger t^7 . When 115 this arm is pressed inward toward the face of the shuttle the tapering or wedge-shaped end of said releasing finger is pressed into a recess in the front of the locking block t^2 and lifts said block out of engagement with 120 the bobbin to release the latter. When the 125 said arm is thrown away from the face of the shuttle, it releases the locking block and permits it to be thrown into locking engagement with the bobbin. This releasing arm 130

and its carrier may be actuated in any desired manner. As here shown said carrier is connected to the front end of a slide bar t^{12} , which extends inward through a suitable fixed bearing t^{13} and is provided at its inner end with a roller stud t^{14} , that travels in a path cam t^{15} , (Fig. 3) formed on the inner face of the large cam disk I. This cam is timed so as to release the bobbin and again 10 lock it at the proper time as hereinbefore stated.

To spread the needle loop for the passage of the shuttle therethrough, I provide a usual loop spreader and lifter w (Figs. 1, 4 15 and 5), the same being supported by a pivot screw w' , upon the free end of a lifter lever w^2 . This lever (Figs. 4 and 5) extends inwardly and is made fast upon a lifter shaft w^3 , mounted in suitable fixed bearings in the 20 machine and at its right-hand end (Fig. 1) has adjustably clamped thereon an inwardly extended cam lever w^4 , shown best in Fig. 2. This cam lever at its inner end, carries a roller stud that enters and travels in a path 25 cam w^5 upon the outer or right-hand face of the large cam disk E (Fig. 1). In the formation of the stitch, as the needle draws its loop upward from the stock, this lifter is moved to engage and lift one side of the 30 loop outward toward the operator, thereby in connection with the inwardly retreating needle, to spread the loop for the proper entrance and passage of the shuttle. As soon 35 as the shuttle picks off the loop from the lifter and needle, the lifter drops back to its normal position preparatory to lifting and opening a new loop. This lifter w may be 40 adjusted by swinging it about its pivot w' upon the lifter arm, it being held in adjustable position on said arm by a clamping screw w^6 , which is extended through a slot in the lifter.

Suitable means for heating the shuttle 45 chamber and its contained bobbin and the other necessary parts of the machine are provided, but the same are common to machines of this type and form no part of my invention.

The operation of the machine will have 50 been made clear from the foregoing description of the various parts and movements.

The machine is much simpler than any machine known to me for performing the 55 same class of work, and in many ways is superior in respect to the results attained by the various movements. For example, there is likely to be a variation in the awl points, due to the grinding thereof, and any variation 60 in the awl point requires the adjustment of the awl carrier and its bracket on the feed slide and with respect to the feed actuating mechanism. This is most conveniently accomplished in my machine (see 65 Figs. 1 and 1^a) by the threaded sleeve e^4 .

The outer thread on this sleeve is relatively coarse and the inner thread relatively fine, both, however, being right threads. The effect of this is that rotation of said sleeve in one or the other direction, causes the awl 70 carrying bracket e to be moved away from the end of the feed lever e^7 , to vary the position of the awl without varying the length of feed imparted to the awl. This sleeve is clamped in its adjusted position by splitting 75 the bearing therefor and providing the clamping screw e^8 (Fig. 1). The top of the feed slide is thus left clear and open to facilitate the manipulation of the shoe. The thread measuring mechanism, in respect to 80 its simplicity, its ease of adjustment, and possible adjustments, is also superior to anything known to me.

The locking of the presser-foot in its various positions, according to the thickness of 85 work, by means of the brake mechanism, is much superior to pawl and ratchet mechanisms heretofore generally used. The brake is more durable, quite as secure, and permits of no lost motion, nor noise.

The thread locking mechanism is also of the simplest and most effective sort and (see 90 Figs. 1 and 4) by means of the split clamp p^x , by which the depending arm p^2 is secured to its shaft p' , permits of ready and 95 sufficient adjustment for various sizes of thread.

The looper mechanism is simple and the length of the looper carrier from the actuating point to the looper tip, is much less 100 than any looper mechanism known to me; consequently, the movements of the looper are more positively controlled and with less wear and tear of the mechanism.

Other advantages due to the simple arrangement, construction and operation of the parts will be evident upon examination, to those skilled in the art, and need not be enumerated herein. The combinations of parts providing these various advantages, 105 are largely referred to in the appended claims.

Obviously, my invention is not limited to the particular embodiment thereof herein shown and described for purposes of illustration, but my said invention may be varied 110 without departing from its spirit and scope as gathered from the present disclosure.

Claims:

1. A sewing machine containing in combination, stitch forming mechanism provided with an awl, a sliding awl carrier, a threaded sleeve mounted therein, a fulcrum support adjustable in said sleeve, a feed lever fulcrumed upon said support and a cam operated actuator for said feed lever and relative to which said feed lever is adjustable.

2. A sewing machine containing in combination, stitch forming mechanism provided with an awl, a sliding awl carrier, a threaded 125

sleeve mounted therein, means to secure said sleeve against rotation, a fulcrum support adjustable in said sleeve, a feed lever fulcrumed upon said support and a cam operated actuator for said feed lever and relative to which said feed lever is adjustable.

3. A sewing machine containing in combination, stitch forming mechanism combining in its organization a thread finger, a reciprocating slide bar therefor, a pivoted slide bar actuator laterally and loosely engaging the said slide bar, and a removable pivot for said actuator, whereby upon removal of said pivot said actuator may be moved away from said slide bar to free the latter for its direct withdrawal from the machine.

4. A sewing machine having stitch forming mechanism combining in its organization a thread finger, a slide bar therefor having a rack, a pivoted segmentally geared

actuator for said rack, and a removable pivot for said actuator.

5. A sewing machine having stitch forming mechanism combining in its organization a thread finger, a slide bar therefor, a cam for reciprocating said slide bar longitudinally, a pivoted actuator operated by said cam and arranged substantially tangential thereto, said actuator laterally and loosely engaging the said slide bar, and a removable pivot for said actuator whereby said actuator may be laterally withdrawn from said slide bar substantially along the cam surface.

In testimony whereof, I have signed my name to this specification, in the presence of two subscribing witnesses.

JOHN J. HEYS.

Witnesses:

FREDERICK L. EMERY,
ROBERT H. KAMMLER.
